CASH RECEPACLE

Earl D. Boisselier, Glen Ellyn, Ill., assignor to
American Flyer Manufacturing Company, Chi-
cago, Ill., a corporation of Illinois

Application February 8, 1936, Serial No. 63,024

4 Claims. (Cl. 235—23)

This invention relates to a toy which simulates the appearance and operation of a standard cash register.

A primary object of the invention is to provide a novel construction which may be produced and assembled at a low cost to provide a realistic toy which is strong, durable, and thoroughly reliable in operation for its intended use, namely, to register or indicate fictitious sales resulting from "make-believe" transactions.

Other special objects of the invention are: to provide a low production cost cash receptacle of the toy class including means for simulating sales receipts such as ordinarily are obtained from a standard cash register; to provide means which may be manipulated to indicate the character of the goods involved in a sale; to provide normally concealed sale amount indicating plates which are moved individually to exposed positions upon depression of the individual keys of the machine and which remain exposed after the keys are released; to provide means operable at will and independently of the keys for releasing said plates to permit them to return from their exposed positions to their normal or concealed positions; to provide a drawer urged constantly toward an open position; to provide novel means for holding said drawer normally closed and for releasing said holding means; and to provide novel means whereby a bell is sounded when the drawer opens.

With the foregoing and other objects in view, which will become more fully apparent as the nature of the invention is better understood, the same consists in the novel features of construction, combination and arrangement of parts as will be hereinafter more fully described, illustrated in the accompanying drawings and defined in the appended claims.

In the drawings, wherein like characters of reference denote corresponding parts in the different views:

Figure 1 is a perspective view of a cash receptacle constructed in accordance with the invention.

Figure 2 is an enlarged transverse section through the cash receptacle.

Figure 3 is a partial top plan view and partial horizontal section through the cash receptacle; and

Figure 4 is a front elevation of the cash receptacle.

Referring to the drawings in detail, it will be observed that the present cash receptacle comprises a casing, designated generally as A, which

closely simulates in shape and general appearance the casing of a standard cash register.

The casing A is formed from sheet metal and comprises a pair of side walls 10, 10, a rear wall, and a combined front and top wall 12, which walls 5 may be joined together, either permanently or detachably, in any suitable manner. Preferably, however, and as shown, the side walls 10, 10 are flanged inwardly to overlie the marginal portions of the walls 11 and 12 and said walls are joined 10 together by means of tabs 13 on the ends of the walls 11 and 12 extending through slits in the side walls 10, 10 and bent over against the outer faces of the latter walls.

The walls 10, 10 are stepped at their front 15 edges so that there is formed at the top of the casing A a relatively narrow compartment 14 and at the bottom of said casing a forwardly extending drawer compartment 15, the combined front and top wall 12 extending downwardly in front 20 of the compartment 14, as at 16, thence forwardly and at a downward inclination, as at 17, thence vertically downward, as at 18, to the top of the drawer compartment 15, thence forwardly over said drawer compartment, as at 19, and finally 25 downward at the front of said drawer compartment as at 20.

Within the casing A behind the portion 18 of the wall 12 is a horizontal shaft 21 which is mounted at its ends in the casing side walls 10, 30 10 and which has rockably mounted thereon at spaced intervals therealong a plurality of key arms 22. These arms are mounted intermediate their ends on the shaft 21 and extend forwardly through vertical slots 23 in the portion 18 of the 35 wall 12 and rearwardly to points approximately underlying the front of the compartment 14. At their outer ends said arms are provided with buttons 24 for finger engagement to depress their outer end portions thus to cause their inner end 40 portions to rise, and preferably, but not necessarily, alternate of said arms are so mounted on the shaft 21 that the buttons 24 are disposed in two or more rows at different elevations, thus to simulate the key arrangement of a standard cash 45 register and at the same time to conserve space and to facilitate the selection and finger actuation of any individual key arm.

Each key arm 22 has pivoted thereto, at its inner end, a latch 25 comprising a forwardly extending portion 26 disposed at one side of the key arm and an upwardly extending portion 27 which, at its upper end, has its front edge sloping downwardly and forwardly, as at 28, to a downwardly facing shoulder 29. Moreover, each 55

key arm has pivoted thereto at its inner end a forwardly directed extension 30 of a related sale amount indicating plate 31, of which there are a number corresponding to the number of key arms.

The plates 31 are vertically disposed and are arranged in two banks, one to either side of the central, vertical, transverse plane of the machine below the compartment 14, with the plates of each bank disposed, from front to rear, successively behind one another. Normally, said plates rest at their lower ends on a forwardly directed extension 32 of a plate 33 which is suitably fastened against the inner face of the rear wall 11 of the casing A, this plate 33 having another forwardly directed extension 34 provided with slots 35 in which the plates 31 are guided at their upper ends, for vertical movement.

The weight of the plates 31 holds the inner ends of the key arms 22 normally depressed and the outer ends of said arms normally elevated, and when said plates are in their normal or lowermost positions resting on the extension 32, their upper ends are disposed below a sight opening or window 36 in the portion 16 of the wall 12. On the upper part of the front face of each plate 31 is a numeral indicating a certain money value corresponding to a like money value indicating numeral on the button 24 of the related key arm 22. Thus, by depressing any given button, the related plate 31 will be elevated and the top portion thereof with the numeral thereon corresponding to the numeral on the depressed button will become visible through the window 36. In this connection, the numerals on the left hand bank of plates 31 preferably are whole numbers indicative of amounts in dollars, and the numeral on the right hand bank of plates 31 preferably indicate fractions of a dollar, so that by depressing different pairs of the key arms total amounts comprising dollars and cents will be indicated by the numerals on the exposed upper end portions of the pair of plates 31 which are elevated.

When, by depression of any given button 24, the related plate 31 is elevated, it is desirable that said plate shall remain elevated after finger pressure is removed from the button. This is accomplished through cooperation of the latches 25 with a keeper 37 which conveniently is in the form of a normally vertically disposed plate fastened to the rear side of a transversely extending, horizontally disposed shaft 38 located above the rear ends of the key arms 22 and rotatably mounted in a pair of ears 39, 39 extending forwardly from the plate 33. Extending upwardly from the shaft 38 through a slot 40 in the portion 17 of the casing wall 12 is a lever 41 having a handle 42 for finger engagement to swing said lever forwardly thus to correspondingly rotate the shaft 38 and, with it, the keeper plate 37 from its normal, vertical position to a downwardly and rearwardly inclined position.

Related to each latch 25 is a spring 43 which tends constantly to rotate the latch to swing its arm 27 forwardly. Each spring is in the form of an arm disposed at the side of the related key arm 22 opposite the side thereof at which the related latch 25 is disposed, and at one end is suitably anchored to the key arm. At its other end it extends through a slot 44 in the key arm 22 and is anchored to the forwardly extending portion 26 of the latch 25. Its tendency is to move downwardly to the lower end of the slot 44 and thus maintain the portions 26 and 27 of the

latch swung downwardly and forwardly, respectively. However, because of the slot 44 in the key arm, it is manifest that the latch may be swung counter to the direction in which it is urged by the spring 43.

The shaft 38 is disposed in a position above the inner ends of the key arms 22 such that the keeper plate 37, when in its vertical position as shown by full lines in Figure 2, overlies the downwardly and forwardly inclined forward edges 28 of the latch portions 27, and such that when any given key arm is actuated to elevate the related plate 31 to an operative position behind the window 36, the related latch is elevated to a position in which its shoulder 29 is disposed above the upper edge of the keeper plate 37. Consequently, when any given key arm is actuated to elevate the related plate 31, the inclined upper, forward edge of the portion 27 of the related latch 25 first engages the lower edge of the keeper plate and by the cam action of said edge 29 with the keeper plate the latch is rocked rearwardly relative to the keeper arm against the force of the spring 43. As upward movement of the key arm continues the portion 27 of the latch 25 finally reaches a position in which its shoulder 29 becomes aligned with the upper edge of the keeper plate, whereupon the spring 43 acts to throw the portion 27 of the latch forwardly to a position as illustrated by dotted lines in Figure 2. The shoulder 29 having thus been engaged over the top of the keeper plate 37, it is apparent that the key arm will be held in its actuated position with the related plate 31 elevated when finger pressure subsequently is removed from the button 24 of the key arm. It is equally apparent that release of the latch may be effected at any time simply by grasping the handle 42 of the lever 41 and pulling said handle forwardly, thereby to effect corresponding rotation of the shaft 38 and tilting of the keeper plate 37 to its downwardly and rearwardly inclined position aforementioned. This results in withdrawing the upper edge of the keeper plate forwardly from beneath the latch shoulder 29 and thereby permits the key arm and the plate 31 to return to their normal positions.

In the portion 20 of the casing wall 12 is an opening 45 in which is slidably mounted the forward end portion of a cash drawer 46 which is urged constantly forward or to an open position by a suitable spring 47. At its rear end said drawer is slidably supported by means of tongues 48, extending from the sides thereof into slots 49 in a pair of guide plates 50 secured against the inner faces of the casing side walls 10, 10. Moreover, projection or opening movement of the drawer is limited by engagement of the tongues 48 with the forward ends of the slots 49.

Normally the drawer 46 is retained in its closed position by a pair of latch arms 51 which extend forwardly from the casing rear wall 11. Preferably these arms constitute the side portions of a U-shaped yoke the bight or connecting portion 52 of which is suitably mounted on the wall 11 for rotation so that the arms 51, 51 may swing vertically. Extending upwardly from the portion 52 is a finger 53 with which cooperates a leaf spring 54 carried by the casing wall 11, whereby the arms 51 constantly are urged downwardly against a supporting rod 55 which extends horizontally from side to side of the casing A and is guided at its ends for vertical movement in slots 56 in the casing side walls 10, 10. At their forward ends the arms 51 are bent downwardly and

rearwardly as indicated at 57, the free ends of said portions 57 thus constituting shoulders and the front edges thereof thus constituting cam surfaces for co-operation with the rear wall of the drawer 46. That is to say, when the rod 55 is disposed at the bottoms of the slots 56 the arms 51 are disposed substantially horizontally above the plane of the top of the drawer 46 so that if the drawer is open and is pushed inwardly to its closed position the upper edge of its rear wall engages the front inclined edges of the arm portions 57 and thereby lifts said arms until the drawer rear wall passes behind the free ends of the arm portions 57, whereupon said arms drop and the free ends of the portions 57 thereof engage the front face of the drawer rear wall and thus latch the drawer closed.

When the drawer is latched in closed position by the arms 51 it obviously is necessary to lift said arms to permit the spring 47 to act to project the drawer to its open position. To lift said arms a key arm 58 is provided. This key arm is pivoted on the shaft 21 and extends from said shaft forwardly through a slot in the portion 18 of the wall 12 and is equipped at its forward end with a button 59 for effecting its depression. It also extends downwardly and rearwardly from the shaft 21 to the rod 55 to which it is suitably connected. Thus, upon depression of the button 59 the key arm is rocked on the shaft 21 and the rod 55 is elevated, thereby lifting the latch arms 51 and releasing the drawer 46 for projection by the spring 47.

To one of the casing side walls 10 is fastened a bell 60, and inwardly of said bell there projects inwardly from said wall 10 a lug 61, while to the rear end of the drawer 46 is fastened one end of a leaf spring 61 which has a free end portion thereof projecting beyond the side of the drawer 40 for engagement with the lug 61 when the drawer moves outwardly. Thus, upon outward movement of the drawer the leaf spring is bent rearwardly by engagement with said lug until it finally passes said lug and is released, whereupon it 45 springs forwardly and a hammer thereon strikes the bell 60, thus causing the bell to ring each time the drawer is opened.

Suitably mounted for rotation within the chamber 14 to one side of the window 36 and behind a second window 62 in the portion 16 of the casing wall 12, is a plural-sided block or its equivalent 63 on the flat, side faces of which are different words or symbols indicative of different kinds of classes of goods. Connected with the block 63 is a knob 64 which is exposed for finger actuation at one side of the casing A for the purpose of rotating said block to bring any side thereof into view through the window 62. If desired, there may be two of the indicating devices 63, 60 one to either side of the window 36.

Against the outer face of one of the casing side walls 10 is suitably mounted an auxiliary casing 65 to contain a roll of paper 66 which may be withdrawn through a slot 67 in said auxiliary casing and be torn off in short lengths to simulate sales slips.

In addition to its heretofore described features, the present cash register includes means whereby depression of a finger engageable element causes a normally concealed "No sale" indicating plate to be brought into view through the window 36 and simultaneously lifts the latch arms 51 to release the drawer 46 to permit its projection to open position by the spring 47. To the under 75 side of the casing wall 17 near one side of the

casing is fastened a bracket 68, and to this bracket is pivoted, intermediate its ends, a lever 69 having forwardly and rearwardly extending arms 70 and 71, respectively. The forwardly extending arm 70 is bent to extend upwardly through a slot 72 in the casing wall 17 and outside of the casing is bent laterally to provide the aforementioned finger engageable element designated as 73. On the other hand, the arm 71 extends to a point near the rear of the casing and at its rear end carries a plate 74 on the front of which is the "No sale" indication. Due to the weight of the plate 74 and the relative length of the arms 71, 72, the constant tendency of the lever 69 is to assume a position in which its arm 70 is elevated and its arm 71 is lowered, with the plate 74 disposed below the window 36 and therefore concealed from view, as shown by full lines in Fig. 2. Therefore, upon depression of the finger engageable element 73 the lever 69 is rocked on its pivot and the "No sale" indicating plate 74 is swung upwardly into view through the window 36, as illustrated by dotted lines in Fig. 2. Moreover, upon release of finger pressure on the element 73 the lever 69 returns to its normal, full line position under the influence of gravity, although a spring may be employed to move said levers to its full line position should that be necessary or desirable.

Preferably, but not necessarily, the lever 69 is connected with the drawer latching means so that upon rocking of said lever to exhibit the "No sale" plate, the drawer latch means is released. As shown, this connection comprises a rod 75 connecting the arm 71 of the lever 69 with one of the drawer latch arms 51 and having a lost motion connection with one or the other of said arms whereby the drawer latch means may be operated by the lever 58 without actuating the "No sale" plate. In the present instance the lost motion connection referred to is formed by having the upper end of the rod 75 operable in a slot 76 in the arm 71 of the lever 69. Normally the laterally bent upper end of the rod 75 is disposed at the bottom of said slot. Therefore, when the lever 69 is rocked to lift the arm 71 the rod 75 is lifted and lifts and releases the drawer latch means. On the other hand, when the lever 58 is actuated to lift and release the drawer latch means, the upper end of the rod 75 simply moves upwardly in the slot 76 without imparting movement to the lever 69.

From the foregoing description considered in connection with the accompanying drawings it is believed that the construction and operation of the invention will be clearly understood. It is desired to point out, however, that while only a single structural embodiment of the invention has been illustrated and described, the same obviously is capable of embodiment in various other mechanical structures within its spirit and scope as defined in the appended claims.

I claim:—

1. In a cash receptacle, a casing, a shaft extending horizontally within said casing, a plurality of key arms pivoted intermediate their ends on said shaft and having their forward portions extending outside of the casing for depression to elevate their rear ends, a plurality of sale amount indicating plates near the back of the casing, one related to each key arm and connected to the rear end thereof for elevation therewith, a latch on each key arm, and a keeper common to the latches of all of said key arms and engageable by said latches to retain any given indicating plate elevated following depression and release 75

of the forward end of the related key arm, said keeper being in the form of a rod rotatable about its longitudinal axis to release any latch engaged therewith to permit the related indicating plate to move downwardly.

- 5 2. In a cash receptacle, a sale amount indicating plate tending constantly to move downwardly to a concealed position, a key arm engaged with said plate and rockable to elevate said plate to an exposed position, a latch pivoted on said key arm, a keeper disposed to be engaged by said latch when said key arm is rocked to elevate said plate, spring means between said latch and said key arm permitting the latch to rock to pass 10 said keeper and effective to rock said latch into engagement with said keeper when the key arm is rocked to elevate said plate to its exposed position, thereby to releasably hold the plate elevated, said keeper being in the form of a rod rotatable about its own axis, said latch being releasable by rotation of said keeper, said keeper having a flat side face disposed adjacent an edge of the latch to force the latter from engagement 15 with the keeper when the latter is rotated, and 20 means for rotating said keeper.

- 25 3. In a cash receptacle, a sale amount indicating plate tending constantly to move downwardly to a concealed position, a key arm engaged with said plate and rockable to elevate said plate to an exposed position, a latch pivoted on said key arm, a keeper disposed to be engaged by said latch when said key arm is rocked to elevate said plate, the key arm having a slot, a spring arm fastened 30 at one end to said key arm and at its other end

extending through said slot and engaged with said latch and tending to rock said latch to its limit of movement as determined by engagement of a part of said spring arm with the wall defining one end of said slot, the keeper being disposed 5 so that when the key arm is rocked to elevate said plate the latch engages and is rocked by said keeper against the force of said spring arm until a position of the latch is reached so that the spring arm rocks the latch into engagement 10 with the keeper to hold the indicator plate elevated, said keeper being rotatable to release said latch, and means for rotating said keeper.

4. In a cash receptacle, a sale amount indicating plate tending constantly to move downwardly 15 to a concealed position, a key arm engaged with said plate and rockable to elevate said plate to an exposed position, a latch pivoted to said key arm and extending upwardly therefrom, said latch having a forwardly extending downwardly facing 20 shoulder, spring means tending constantly to swing said latch forwardly, and a rotatable latch keeper behind which said latch travels when the key arm is rocked to elevate said plate and across the top of which said shoulder is moved by said 25 spring means when the latch is elevated to a predetermined position, the latch keeper having a rear flat face against which the forward edge of the latch is urged by said spring means when the latch shoulder is disposed above said keeper 30 whereby rotation of said keeper swings the latch rearwardly to assist in effecting its disengagement from said keeper.

EARL D. BOISSELIER.
